(57) **CLAIM**

The ornamental design for a cosmetic container with slideable tray, as shown and described.

DESCRIPTION

FIG. 1 is a top perspective view showing the first embodiment of my new design with its cover in a closed position and its slideable tray in an inward position;

FIG. 2 is a front end elevational view showing the cover in its closed position and the tray in its inward position;

FIG. 3 is a back end elevational view showing the cover in its closed position and the tray in its inward position;

FIG. 4 is a left side elevational view showing the cover in its closed position and the tray in its inward position;

FIG. 5 is a top plan view showing the cover in its closed position and the tray in its inward position;

FIG. 6 is a bottom plan view showing the cover in its closed position and the tray in its inward position;

FIG. 7 is a top perspective view showing the cover in its open position and the tray in its inward position;

FIG. 8 is a front end elevational view showing the cover in its open position and the tray in its inward position;

FIG. 9 is a back end elevational view showing the cover in its open position and the tray in its inward position;

FIG. 10 is a left side elevational view showing the cover in its open position and the tray in its inward position;

FIG. 11 is a top plan view showing the cover in its open position and the tray in its inward position;

FIG. 12 is a top perspective view showing the cover in its open position and the tray in its outward position;

FIG. 13 is a left side elevational view showing the cover in its open position and the tray in its outward position;

FIG. 14 is a top plan view showing the cover in its open position and the tray in its outward position;

FIG. 15 is a bottom plan view showing the cover in its open position and the tray in its outward position; and,

FIG. 16 is a top perspective view of the second embodiment of my design showing the cover in its open position and the tray in its outward position. With the exception of the make-up shown in the three containers, all other views of the second embodiment are identical to the first embodiment.
